UNITED STATES PATENT OFFICE.

EMIL R. LOCHMAN, OF ST. LOUIS, MISSOURI.

CARVING-MACHINE.

No. 850,941.

Specification of Letters Patent.

Patented April 23, 1907.

Application filed January 2, 1903. Serial No. 137,529.

To all whom it may concern:

Be it known that I, EMIL R. LOCHMAN, a citizen of the United States, residing at St. Louis, State of Missouri, have invented certain new and useful Improvements in Carving-Machines, of which the following is a full, clear, and exact description, reference being had to the accompanying drawings, forming a part hereof.

10 My invention has relation to improvements in carving-machines; and it consists in the novel construction and arrangement of parts more fully set forth in the specification and pointed out in the claims.

15 In the drawings, Figure 1 is a perspective view of a section of the machine, showing my improvement attached thereto. Fig. 2 is a side elevation of the outer swinging frame of the machine. Fig. 3 is a section on line 3 20 3 of Fig. 2, and Fig. 4 is a section on line 4 4 of Fig. 2.

The present invention is an improvement on carving-machines provided with one or more swinging frames or parallelograms, said 25 improvement being particularly directed to the belt connections between the main drive-shaft and the tool-spindles, to the means for imparting the necessary tension thereto, and to the means for insuring a high velocity to 30 the tool-driving belt without subjecting the same to unnecessary torsional strain. In the general class of machines of this type a single belt connection is interposed between the main drive-shaft and each tool-spindle, the 35 laps of the belt passing around guide-pulleys mounted on a bracket which is suspended on the post about which the outer frame of the machine revolved. Under this arrangement the path of the drive-belt becomes unduly 40 circuitous, necessitating the travel of the belt around corners and numerous bends and subjecting the same during the travel thereof to variable degrees of torsion. This torsional strain, coupled with the high velocity 45 to which such a belt is necessarily subjected, has the effect of shortening the life thereof, and often during the running of the machine the belt would part and entail both a loss of time and material.

50 My present improvement contemplates the disposition of two belt-sections between the main drive-shaft and each tool-spindle—namely, an inner section traveling at one velocity, disposed between the main drive-shaft and the post at the outer end of the inner frame of the machine, and an outer belt-section

disposed between said post and the free end of the outer frame, said outer section being herein designated as the "tool-driving belt" and traveling at a higher velocity. The 6c tool-driving-belt sections are made lighter than the inner belt-sections, the tighteners being applied directly thereto, the heavier material of which the inner sections are composed dispensing with the necessity of belt-tighteners. In detail the invention may be described as follows:

Referring to the drawings, 1 represents the upper supporting-bracket for the support of the inner vertical swinging frame 2. Pivotally mounted between the outer or free ends of the upper and lower members (not shown) of the inner frame is the angular post 3, said post constituting the pivotal axis about which the outer frame of the machine revolves. This outer frame (or extension) comprises the post 3 referred to, a series of vertically-oscillating arms 4, (only the top one of which is shown,) pivotally embracing the post 3 at approximately their medial portions, the rear connecting-post 5, and the front tool-supporting beam 6. In the particulars mentioned the present machine conforms to machines of a class well known in the art, and no detailed description thereof is required. Like in machines of this class the main drive-shaft 7 is concentric with the axis of oscillation of the inner frame and has disposed thereon belt-pulleys 8, corresponding in number to the number of tools 9, (only one tool being herein shown,) carried by the beam 6. Pivotally secured to the inner face of one of the walls (the wall which is parallel to the plane of oscillation of the arm 4) of the post 3 is the inner end of a bar 10, said end having 85 deflected therefrom a bracket 11, serving as a support for the spindle of the step-pulley 12. Over the smaller periphery of the pulley 12 is passed the inner belt-section 13, leading from the belt-pulley 8, and over the 90 larger periphery is passed the outer belt-section 13', leading to the pulley 14 of the tool-spindle, the belt 13' previously passing through the pulley-block 15, as in the previous class of constructions referred to. The 95 bar 10 is pivotally coupled to the adjacent arm 4 by a link 16, whose point of connection with the bar 10 is at a slight distance from the outer end of the latter. The point of connection of the bar 10 with the post 3 is 100 slightly in advance of the vertical plane passed through the axis of vertical oscillation 105

tion of the arm 4, so that a line drawn from such point of connection along the wall of the post 3 to the axis of vertical oscillation of the arm 4 would be slightly inclined from the vertical, the link 16 being substantially parallel to such a line, Fig. 2. The link 16, arm 4, bar 10, and so much of the post 3 as is included between the point of connection of the bar 10 therewith and the axis of vertical oscillation of the arm 4 constitute a parallelogram of pivoted links which is free to fold and unfold, according to the degree of vertical oscillation imparted to the outer frame. The specific location of the point of connection between the bar 10 and post 3 is made necessary, owing to the slight distance that the axis of rotation of the tool-spindle occupies in advance of the point of connection of the arm 4 with the tool-supporting beam 6; otherwise the parallelism of the sides of the parallelogram would not be conserved during the vertical oscillations of the arm 4.

The outer end of the bar 10 has formed therewith the ratchet-disk 17, disposed at right angles to the plane of oscillation of said bar, the middle of the ratchet supporting a stud 18, about which is mounted the boss of an arm 22, about which boss is coiled the body of the belt-tightener spring 19, one end of the latter being secured to a pawl 20, engaging the ratchet-teeth, and the opposite end of a lug 21 on the under surface of said arm, the latter being freely rotatable about the stud and the free end of said arm 22 carrying a pulley 23. To wind up the spring, either the pawl 20 can be run along the teeth of the ratchet or the arm 22, carrying the pulley, can be swung in the opposite direction to produce the same result.

The connection between the bar 10 and post 3 brings the axis of rotation of the step-pulley 12 substantially in line with (slightly to one side of, in reality) the axis of rotation of the post, so that the oscillation of the pulley in a vertical plane to which it is subjected for any vertical sweep of the arm 4 cannot materially disturb the travel of the inner belt-section 13. As to the outer belt-section, the disposition thereof relatively to the pulley 12, pulley 14, and tightener-pulley 23 is not disturbed during any vertical oscillation of the outer frame, since the parallelogram of pivoted links referred to always preserves the several parts in constant relation—that is to say, the bar 10 oscillates parallel to the arm 4, the planes of rotation between the several pulleys are preserved in constant relation, the belt-tightener following the outer belt-section in all its oscillations and permitting the belt to travel at an increased speed over the inner belt-section, and this without subjecting the outer belt to any torsional strain under any circumstances.

Thus it will be seen that all the advantages specified above are inherent in the pres-

ent construction. The series of tools at the free end of the outer frame may of course be any number from one up, and the expression "series of tools" as used in the claims is to be interpreted as covering one or more tools.

Having described my invention, what I claim is—

1. In a carving-machine, a frame swinging about an axis, a tool at the free end of said frame mounted to oscillate in a plane parallel to said axis, a pulley mounted substantially in the line of the axis of the frame, the axis of the pulley being capable of oscillation in a plane parallel to the plane of oscillation of the tool aforesaid, a belt-tightener coupled in position near the axis of said pulley and oscillating in unison therewith, and a belt-section leading from the pulley to its corresponding tool-spindle, substantially as set forth. 75

2. In a carving-machine, a frame swinging about an axis, and adapted to sweep in planes parallel to said axis, a tool at the free end of said frame, a pulley mounted substantially in the line of the axis of the frame, the axis of the pulley being capable of oscillation in a plane parallel to the planes of the sweep of the frame, a belt-tightener co-operatively connected with the pulley and oscillating in unison therewith, a link connecting said tightener with the frame, and a belt-section leading from the pulley to its corresponding tool-spindle, substantially as set forth. 90

3. In a carving-machine, a suitable frame swinging about an axis, a second frame swinging on said frame about a second axis, a tool at the free end of the second frame adapted to sweep in a plane parallel to said second axis, a drive-shaft located in the line of the axis of suspension of the first frame, a step-pulley for the tool located at the axis of suspension of the second frame, said pulley being adapted to oscillate about its axis of rotation in planes parallel to the sweep of the tool aforesaid, an inner belt-section leading from the drive-shaft to the smaller periphery of the step-pulley, and an outer belt-section leading from the larger periphery of the step-pulley to the tool-spindle, substantially as set forth. 100

4. In a carving-machine, a suitable frame swinging about an axis, a second frame swinging on said frame about a second axis, a tool at the free end of the second frame adapted to sweep in a plane parallel to the second axis, a drive-shaft located in the line of the axis of suspension of the first frame, a step-pulley for the tool located at the axis of suspension of the second frame, said pulley being adapted to oscillate with its axis of rotation in planes parallel to the sweep of the tool aforesaid, an inner belt-section leading from the drive-shaft to the smaller periphery of the step-pulley, an outer belt-section leading from the larger periphery of the step-pulley to the tool-spindle, substantially as set forth. 110

ley to the tool-spindle, and a belt-tightener for the outer belt-section coupled to the step-pulley and oscillating in unison therewith, substantially as set forth.

- 5 5. In a carving-machine, a suitable frame swinging about an axis, a second frame swinging on said frame about a second axis, a tool at the free end of the second frame adapted to sweep in planes parallel to said second 10 axis, a drive-shaft located in the line of the axis of suspension of the first frame, a step-pulley for the tool located at the axis of suspension of the second frame, the axis of the pulley being free to oscillate in planes parallel to the sweep of the tool, an inner belt-section leading from the drive-shaft to the smaller periphery of the step-pulley, an outer belt-section leading from the larger periphery of the step-pulley to the tool-spindle, 15 a swinging bar coupled in position about the axis of the pulley and adapted to oscillate in unison, and in a corresponding plane, therewith, a link connecting said bar to the second frame, and a belt-tightener for the outer belt-section carried by said bar, substantially as 20 set forth.
- 25 6. In a carving-machine, a suitable frame swinging about an axis, a second frame swinging on said frame about a second axis, the tool at the free end of the second frame 30

adapted to oscillate in planes parallel to said second axis, a drive-shaft located in the line of the axis of suspension of the first frame, a bar opposite the tool, pivotally connected about the axis of suspension of the second 35 frame, a bracket carried by said bar, a step-pulley mounted on said bracket and having its axis disposed substantially in the line of the axis of suspension of said second frame, a ratchet at the outer end of the bar, a stud on 40 said ratchet, a spring coiled about the stud, an arm swinging about the stud, a tightening-pulley on the free end of said arm, one end of the spring engaging the ratchet and the other end being secured to the swinging arm, a 45 link coupling the bar pivotally to the outer or second frame, an inner belt-section leading from the drive-shaft to the smaller periphery of the step-pulley, and an outer belt-section leading from the larger periphery of the step-pulley to its corresponding tool-spindle, the tightening-pulley engaging one lap of the outer belt-section, substantially as set forth.

In testimony whereof I affix my signature in presence of two witnesses.
